UNITED STATES PATENT OFFICE.

GEORGE E. HUNTER, OF ELGIN, ASSIGNOR TO THE ELGIN NATIONAL WATCH COMPANY, OF CHICAGO, ILLINOIS.

SYSTEM FOR ADJUSTING TO TEMPERATURE WATCH-BALANCES AND HAIR-SPRINGS.

SPECIFICATION forming part of Letters Patent No. 484,796, dated October 25, 1892.

Application filed January 26, 1892. Serial No. 419,271. (No model.)

To all whom it may concern:

Be it known that I, GEORGE E. HUNTER, a citizen of the United States, residing at Elgin, in the county of Kane, and in the State of Illinois, have invented certain new and useful Improvements in Systems for Timing and Adjusting to Temperature Watch-Balances and Hair-Springs; and I do hereby declare that the following is a full, clear, and exact description thereof, reference being had to the accompanying drawings, in which—

Figure 1 is a perspective view of the vibrator employed. Fig. 2 is a plan view of the same. Fig. 3 is a cross-section of the vibrator upon line x x , Fig. 2. Fig. 4 is a central longitudinal section, some parts being shown in side elevation. Fig. 5 is a like view of the casing of said vibrator and shows in side elevation the electrically-operated levers employed for releasing the vibrating train. Fig. 6 is a plan view of the upper side of the same. Fig. 7 is a like view of the disk and clutch which operate directly to arrest and release the vibrating train. Fig. 8 is a front elevation of the armature employed for actuating the said releasing mechanism. Fig. 9 is a perspective view of the mechanism of the time-switch, the casing being broken away to show the arrangement of parts. Fig. 10 is a rear elevation of the same, the casing being in section. Fig. 11 is a section of said switch on line x x of Fig. 10. Fig. 12 is a like view of the same upon line x' x' of Fig. 10. Fig. 13 is a plan view of the indicator and recorder and their connecting mechanism. Figs. 14 and 15 are respectively side and end elevations of the same. Fig. 16 is an enlarged plan view of the mechanism employed for setting the hands to zero. Fig. 17 is a like view of the mechanism for connecting the recording and indicating mechanism with the actuating device. Fig. 18 is a plan view of the lower side of the recorder and indicator. Fig. 19 is a section of the same upon line x^2 x^2 of Fig. 13, and Fig. 20 is a plan view of the various parts of my mechanism and shows their relation to each other when arranged for use.

Letters of like name and kind refer to like parts in the several figures.

My invention relates to the timing and ad-

justing of watch-balances and hair-springs before the same are placed in watch-movements; and such invention consists in the method employed, substantially as and for the purpose hereinafter specified.

55

In the carrying of my invention into practice each balance or hair-spring is vibrated a predetermined number of times within or in connection with a device that corresponds to the time-train for which it is intended and the time required for such vibrations is accurately measured and registered. The vibrator preferably used, as shown in Fig. 1, consists, essentially, of an ordinary time-train A, enclosed within a casing B and adapted to be operated by a spring or a weight in any usual manner. For testing balances the usual balance is omitted from the movement and the balance-arbor C provided with a standard hair-spring D and upon or within its projecting end is adapted to receive and hold a balance E, while for testing hair-springs a standard balance is attached to the arbor, the hair-spring is omitted, and provision made for the ready attachment and removal of hair-springs to be tested. The fourth arbor a of the time-train A projects downward below the casing B and upon its end has secured a disk F, while directly below the same and in a line therewith axially is a second larger disk G, which is carried by an independently-journalized arbor H. Said disk is provided upon its upper face with a ring g, that is cut apart at one point and has such diameter of interior as to cause it to encircle said disk F and embrace the periphery of the latter with sufficient force to cause said disk G to rotate with said disk F. The ring g is attached at one end only to its disk G, and may be opened when desired, so as to leave the disk F free. Such operation is effected by means of a lever I, which is secured upon a shaft K, that is journalized horizontally and transversely within the casing B and is provided with an arm i, that extends upward and by a movement of said lever in one direction is caused to enter between and to separate the ends of said ring, while by an opposite movement of said lever said arm will be withdrawn and said ring again permitted to close. To facilitate 95

70

75

80

85

90

95

100

such operation, the disk G is provided with a peripheral notch g' at the point where said ring is divided, which has such size and shape as to permit said arm to be moved inward 5 sufficiently to open said ring. The lever I is provided at one end with a permanent weight i' , while upon its opposite portion, which is threaded, is provided a second weight i^2 , that is adapted to travel over such threaded portion 10 and enables such adjustment of said parts as to cause said arm i to have a normal tendency to engage with said cut ring, so as to arrest the motion of said disk G, but not with sufficient force to cause said ring to 15 open.

The shaft K is supported upon or within insulating bearings and is provided with a collar K, that has a binding-screw k' , from which a flexible wire L extends to a binding-post M 20 outside of the casing, while secured upon or forming part of the threaded portion of the lever I is a spring v^3 , that is adapted to impinge upon a contact-screw N, which is provided at such point and suitably insulated 25 from said casing.

Pivoted at one end within the end of the casing B adjacent to the contact-screw N is a lever O, which has the form shown in Fig. 5 and at its free forked end o has pivoted a 30 finger P with a tail-piece p , which rests normally upon the upper face of said lever-arm and is held in such position with a yielding force by means of a spring o' . From its pivotal connection with said lever said finger 35 extends forward and downward and at its end is adapted to engage with the end of an arm Q, which is secured to and extends from the shaft K. At or near the longitudinal center of the lever O is pivoted one end of a 40 rod R, which from thence extends downward to and is connected with an armature r, which armature is adapted to be acted upon by magnet-coils S and S, that are located beneath the same. A spring T, placed around the rod 45 R and having its ends confined between a collar r' upon the latter and a guide u, which projects from the bracket U, that supports said magnet-coils, operates to hold said rod and said lever O with a yielding pressure at 50 the upper limit of their motion, while by the application of a current of electricity to the magnet-coils said parts through the armature r will be moved to the lower limit of their motion, and during such movement the 55 finger P will engage with the arm Q and give to the shaft K a partial rotation and move the arm i out of engagement with the cut ring g . As said arm Q and finger P move downward below their pivotal bearings, their 60 ends will move apart until at a predetermined point the latter slips off from the former and the lever I is permitted to resume its normal position.

When the ring g is engaged with the disk 65 F and is unobstructed, it moves with the latter and carries with it the disk G, and when

the arm i is permitted to engage with the ends of said cut ring all motion of the time-train is arrested; but by a further inward movement of said arm said cut ring may be 70 opened, so as to release said disk F and permit said time-train to move again. Such release is effected by means of a rod V, which extends longitudinally inward through one end of the casing B with its inner end adjacent to the upper end of said arm i . At its outer end said rod is provided with a push-button, and by means of a suitable spring it is held at the outer limit of its motion, as shown, and when moved to the inner limit of 80 its motion by the operator's hand will engage with and move said arm i into the notch g' of said disk G and spread said cut ring, so as to release the time-train.

It will be seen that after a balance has been 85 placed in position an inward movement of the push-rod V will spread the cut ring g' and enable the time-train to start, while by the application of an electric current to the coils S and S the lever O will be drawn downward, 90 and through the finger P and the arm Q the shaft K will be turned so as to withdraw the arm i from engagement with said cut ring, when the latter will close and the disk G instantly commence to rotate with the disk F 95 of said time-train. After the withdrawal of the arm i from engagement with the cut ring g it is intended that the latter shall make one entire revolution and that said arm shall then automatically engage with the same and 100 instantly arrest its movement and the motion of the time-train. This operation is effected as follows: Pivoted near its center upon the cock h, which journals the arbor H, is a plate W, which has the form shown in Fig. 7, the 105 portion upon one side of its pivotal bearing being provided with an elongated opening w, that spans said shaft and permits the plate to be oscillated upon said bearing the required distance. The opposite end of said plate is 110 forked, and one of its arms w' has such length as to cause its end to project slightly beyond the periphery of the disk G, while the opposite arm w^2 extends outward beyond said disk and then curves toward said arm w' . When 115 the arm i is moved out of contact with the cut ring g , it strikes against the curved arm w^2 of the plate or detent W and moves the free end of the latter so as to cause its arm w' to project partly across the notch g' of the disk G, so that when said arm is permitted to be 120 moved inward again by the weight i' it will impinge upon and be supported by said arm w' . After the movement of said disk has caused the cut portion of said ring g to pass beyond said arm i a pin g^2 , secured within and projecting downward from said disk, engages with a tail-piece w^3 upon said detent and swings the latter in an opposite direction 125 until said arm w' passes out of engagement with the arm i , which arm then moves inward until it rests upon the periphery of said disk, 130

where it remains until the further rotation of the latter brings the cut portion of said ring into position to permit said lever-arm to move inward into engagement therewith and thereby instantly arrest the motion of the time-train.

In connection with the vibrator described I employ a standard clock and two registering mechanisms, which, for the purpose of distinguishing them, I call, respectively, a "recorder" and an "indicator." These registering devices are driven at a uniform velocity by any suitable motor and are adapted to be readily connected with and disconnected from such motor. The recorder is controlled by the vibrator and is intended to run as long as the balance requires to make the number of vibrations representing one minute of correct time, while the indicator is controlled by the clock and when set in motion is intended to run precisely one minute. The vibrator, recorder, and indicator being simultaneously started, the time in excess of or less than one minute which is necessary for producing the representative vibrations will show how much said balance is slow or fast. The recorder and indicator have preferably the same construction and consist, essentially, of a casing X, having suitable registering mechanism that is adapted to show upon a dial Y or upon dials Y and Y', the number of revolutions of a driving-arbor Z. Said registering mechanism is provided with the usual means for setting the hands or other indicating devices at zero before each trial. For such purpose I preferably employ heart-shaped cams and a bar which is operated by a push-button A', as shown in Fig. 16.

For driving the registering mechanisms I show an electric motor A², which is secured upon or connected with a shaft B', that extends transversely beneath the recorder and indicator, as shown. From such shaft there is driven a vertically-arranged arbor C', which at its upper end is provided with a finely-toothed wheel D', that occupies the same plane as and is near to a similar wheel E', which is secured upon the lower end of the arbor Z. Pivoted at the intersection of its arms is an L-shaped bar F', which has journaled upon the end of one of its arms f' a toothed wheel G', which has preferably about twice the diameter of the wheels D' and E' and by a movement of said bar upon its pivotal bearing may be caused to engage with and connect said wheels, so as to cause a rotation of one to be communicated to the other, while by an opposite movement of said bar said intermediate wheel will be moved out of such engagement. The opposite arm f² of said bar forms or is attached to an armature which by the action of magnet-coils H' and H' may be moved so as to cause engagement between said wheels D', E', and G', while a spring I', engaging with the end of said arm

f², operates to hold said parts normally out of engagement.

The mechanism employed for connecting the clock with the indicator is shown in Figs. 9 to 12, and is constructed as follows, viz: Secured upon a horizontally-journalized hollow shaft J' is a disk K', that at one point of its periphery has inserted a piece of insulating material k² and has constant engagement of periphery with an electric spring L'. Upon said shaft is also secured a toothed wheel M', which has sixty teeth and is engaged by a like wheel N', that is attached to and adapted to rotate with a ratchet-wheel O', which is provided with sixty-two teeth o'.

The disk and other parts described are inclosed by a casing P, which has the form shown, and in the lower portion of the same is placed two magnet-coils Q' and Q', and beneath the same is an armature R', which is pivoted at one end to said casing and by means of an intermittent current of electricity passing through said coils may have a vertically-reciprocating motion produced at its free end. To said free end is secured a bar S', which from thence extends upward beside the ratchet-wheel O' and at its upper end s' is adapted to engage with the teeth o' at each upper movement of said armature. A spring s², bearing against the outer side of said bar or pawl, operates to hold the same in normal contact with said ratchet-teeth, so as to insure the engagement of said parts whenever said armature moves upward, while permitting its engaging end to trip over said teeth when said armature and ratchet bar or pawl move downward, the arrangement of parts causing the disk K' to be given a step-by-step rotation whenever an intermittent or interrupted electric current is applied to the magnet-coils. Such result is secured by connecting said coils electrically with an accurate clock T', so that each beat of its pendulum t' sends through them an electric impulse that gives motion to said armature and causes through the same and the connected mechanism a partial rotation of said disk K'.

The disk K' is intended to make nearly a complete revolution and then automatically stop. This is effected by means of a pin k³, which projects from one of the faces of said disk near its periphery and is adapted to engage with an arm s³, that projects upward and inward from the pawl S', and by such engagement to press the latter outward until it no longer engages with the teeth of the ratchet-wheel O'. At the instant when such disengagement of said pawl is effected the contact-spring L' engages with the insulating piece k², for purposes hereinafter described. To relieve the disk from such stoppage, I employ a rod V', which projects downward through the casing P' and is supported by means of a spring u' with its lower end just above said pin k³ after the latter has moved

said pawl out of engagement with said ratchet-wheel and is adapted to have a limited longitudinal motion. A downward pressure upon the upper end of said rod will cause its 5 lower end to engage with said pin and to move the same downward until out of engagement with the pawl-arm s^3 , when said pawl will again engage with said ratchet-wheel and give to the same the step-by-step 10 motion. The contact-spring L' is connected by a wire l' with magnet-coils of the indicator, while a second wire V' connects said indicator and the vibrator with a contact-spring W' , that is arranged to bear against 15 one side of the disk K' .

The mechanism thus combined is used as follows, viz: The operator, having set the recording and indicating devices at zero, places a balance in position within the vibrator and 20 by an inward pressure upon the rod V releases the time-train and permits it to run. After said balance has attained its maximum arc of vibration the operator pushes down upon the rod V' , so as to cause the ratchet-wheel O' to be engaged by the pawl S' , and by such movement turns the disk K' until the insulating-piece k' has passed the contact-spring L' , which closes the circuit through the magnet-coils S and S of the vibrator and 25 the magnet-coils H' and H' of the indicator, and causes the time-train of the former and the indicating mechanism of the latter to move. The retraction of the lever-arm i from 30 engagement with the cut ring g of the vibrator produces contact between the spring i^3 and screw N and, closing the circuit through the magnet-coils H' and H' of the recorder, causes the mechanism of the latter to be set 35 in motion. When the clock has beat sixty times, the rotation of the disk K' has brought the insulating-piece k' beneath the contact-spring L' and, breaking the circuit, releases the armature r of the vibrator, so as to permit the lever O to return to its upper normal 40 position, and at the same time releases the armature f^2 of the indicator, so as to cause the indicating mechanism to instantly stop. When the balance has vibrated the predetermined number of times, whether before, 45 at, or after the expiration of sixty seconds, the movement of the locking-arm i causes the contact-spring i^3 and screw to separate and by thus breaking the circuit effect the instant stoppage of the recorder mechanism. This 50 method may also be employed for the compensation of balances, for which purpose it will only be necessary that the vibrator be run in extremes of temperature and the errors noted and corrected in the usual manner.

55 The apparatus shown and described is not not claimed herein, but is the subject-matter of a separate application filed on an even date herewith and having the Serial No. 419,272.

60 Having thus described my invention, what I claim is—

1. The method employed for testing bal-

ances and hair-springs, which consists in vibrating the same a predetermined number of times in connection with a standard that is 70 actuated for an interval of time which an accurate balance or spring would take to make such number of vibrations and noting the relation between the balance or spring and the standard at the conclusion of the vibrations and the interval of time, respectively, 75 substantially as and for the purpose described.

2. The method employed for testing balances and hair-springs, which consists in vibrating the same the number of times which a standard balance or spring would vibrate during a predetermined interval of time, simultaneously starting two registering devices and actuating one of the same during the 85 vibration of the balance or hair-spring and the other during the predetermined interval of time, substantially as and for the purpose specified.

3. The method employed for testing balances and hair-springs, which consists in vibrating the same the number of times which a standard balance or spring would vibrate during a predetermined interval of time in connection with a registering device, stopping the latter when such number of vibrations is made, and actuating in connection with the vibration of said balance or spring a second registering device for the predetermined interval of time, substantially as and 90 for the purpose shown.

4. The method employed for testing balances and hair-springs, which consists in vibrating the same the number of times which a standard balance or spring would vibrate 105 during a predetermined interval of time, simultaneously starting two similar registering devices and actuating them at the same speed and stopping one of said devices simultaneously with the completion of the number of 110 vibrations of the balance or spring and stopping the other simultaneously with the expiration of the predetermined interval of time, substantially as and for the purpose set forth.

115 5. The method employed for testing balances and hair-springs, which consists in vibrating the same in connection with a registering device the number of times which a standard balance or spring would vibrate 120 during a predetermined interval of time and simultaneously operating a standard time-piece during such interval of time in connection with a separate registering device and then comparing the registrations of the devices, substantially as and for the purpose 125 shown and described.

6. The method employed for testing balances and hair-springs, which consists in vibrating the same the number of times which a standard balance or spring would vibrate 130 during a predetermined interval of time simultaneously with the operation of a standard timepiece during such interval and in

connection with two registering devices whose operation is commenced simultaneously and one of which is stopped when the number of vibrations has been made, while
5 the other is stopped at the expiration of the predetermined interval of time, substantially as and for the purpose specified.

In testimony that I claim the foregoing I have hereunto set my hand this 19th day of November, 1891.

GEORGE E. HUNTER.
